SPOON OR SIMILAR ARTICLE

Frank R. Perry, Oneida, N. Y., assignor to Oneida Ltd.,
Oneida, N. Y., a corporation of New York

Application April 26, 1957, Serial No. 45,910

Term of patent 14 years

(Cl. D54—12)

FIG. 2.

FIG. 5.

FIG. 1.

FIG. 3.

FIG. 4.

Fig. 1 is a front elevational view of a spoon showing my new design;

Fig. 2 is a rear elevational view of the spoon;

Figs. 3 and 4 are sections on the respective lines 3—3 and 4—4 of Fig. 1; and

Fig. 5 is a side elevational view.

The essential features of my design for a spoon or similar article reside in the configuration of the handle in combination with the particular type of ornamentation as applied thereto.

I claim:

The ornamental design for a spoon or similar article, substantially as shown and described.
